UNITED STATES PATENT OFFICE.

HENRY A. LAGE, OF MERCED, CALIFORNIA.

LAND-LEVELER.

1,294,812.

Specification of Letters Patent. Patented Feb. 18, 1919.

Application filed January 31, 1916. Serial No. 75,308.

To all whom it may concern:

Be it known that I, HENRY A. LAGE, a citizen of the United States, residing at Merced, in the county of Merced and State of California, have invented new and useful Improvements in Land-Levelers, of which the following is a specification.

This invention relates to land levelers of the type shown and described in my pending application Ser. No. 830,657, filed April 9, 1914; and has for its object to simplify and improve the construction and operation of such devices.

In producing a practical and efficient leveler adapted for use with a tractor and operating on furrowed or uneven ground, it is important, in order to prevent fluctuations in the elevations of the scraper blade to dispense with wheels at the front of the device and to arrange the carriage wheels therefor at the rear of the frame and in the wake of the scraper, so that they ride upon the surface which has already been leveled and thus serve to maintain the blade at a constant elevation. To relieve all strains from the frame the scraper blade should be carried by draft links, which connect at their front directly with a coupling member which receives the tractor draft connection, and their point of connection in front should be above the line of the carriage wheel centers in order to throw a constant and even load on the carriage wheels and exert a longitudinal strain upon the frame instead of a down-thrust. A further requirement is the employment of an elevated frame, beneath which the scraper blade is suspended, so that the frame may be of narrow construction while the blade can be as wide as desired.

The foregoing desiderata are provided for in the present device, and in addition I employ simple and easily controlled power operated means for raising and lowering the blade and improved and simplified connections between the blade and draft coupling member on the frame and between the blade and controlling mechanism.

One form which my invention may assume is exemplified in the following description and illustrated in the accompanying drawings, in which—

Figure 1 shows a plan view of a device embodying my invention.

Fig. 2 shows a side elevation of the same. Fig. 3 shows a diagram illustrating the advantageous operation of the carriage

wheels by reason of their location behind the scraper blade.

Fig. 4 shows a rear elevation of the device shown in Figs. 1 and 2.

Fig. 5 shows a detail of the jointed connection between the adjustable rack-bar and the scraper blade.

Fig. 6 shows a detail sectional view of the friction cone clutch and driving mechanism therefor employed in the device.

Referring in detail to the accompanying drawings, I have shown a narrow, A-shaped frame 10, formed of channel side bars, upwardly inclined and rearwardly diverging and supported at their rear upon carriage wheels 11, by means of raised bolster members 12. A rigid coupling member 13 is fitted to the front end of the main frame on a line above the axle of the carriage wheels and pivotally receives a draft connection 14 carried by a tractor or other power device, not shown. The coupling member 13 extends rearwardly and downwardly a slight distance where it pivotally receives three draft bars 15; one running centrally to the rear and the remaining two diverging laterally therefrom, all being in turn pivotally connected to the lower edge of the scraper 16 at three points thereon. The scraper, preferably, has a concaved rear portion carrying a sharpened blade 17 and provided with attached sides 18.

On the back of the scraper is a pair of spaced angle bars or cleats 19, extending vertically to a point above the frame where they rest against and are guided by rollers 20, carried by brackets 21 connected to the frame bars. Thus the scraper is drawn from its lowermost portion and is retained against rearward movement at its upper portion by means of the cleats and rollers described. Pivotally connected to the intermediate portions of the cleats 19, by means of the bent coupling pins 22, shown in Fig. 5, are respective rack-bars 23, extending upwardly through guide yokes 24 and held in mesh with pinions 25, carried upon a transverse shaft 26 journaled on standards 27 carried by the frame.

Power operated means are provided for the shaft 26, through a sprocket wheel 28 thereon having a chain connection 29 with a driving sprocket-wheel 30 carried on the axle of the wheels 11. Said sprocket-wheel 28 is loose upon the shaft 26 and carries a friction cone clutch member 31 and is shift-

able by a lever 32 to cause said clutch member to engage and disengage a co-operating clutch member 33 fixed upon said shaft. A friction brake band 34 fits over the clutch member 33 and is operated by a foot pedal 35 to hold said clutch member, and consequently the shaft, against turning, whereby to control the position of elevation of the scraper. A hand-wheel 36 is provided for the shaft 26, being preferably connected with the clutch member 33 and is for the purpose of permitting manual adjustment of the scraper blade vertically in either direction.

The yoke members 24 are rigidly connected to the standards 27 and have bifurcated ends fitted with rollers 37 which engage the rear flattened surface of the rack-bars 23 and serve to hold said bars in a vertical plane in mesh with the pinions 25. The upper ends of the cleats 19 being held against rearward movement afford, in connection with the rack-bars 23, a pivoted link connection between the raising and lowering mechanism and the scraper which is locked for the purpose of permitting the scraper to be forcibly moved downward by the adjusting mechanism and flexes to permit a slight change in the angular relation of the parts necessary for raising the scraper. The coupling pins 22 are also preferably adjustable upon the cleats 19, through the provision of a series of openings 22^a therefor, whereby the distance between the operating mechanism and the scraper may be adjusted.

The friction clutch mechanism employed is advantageous in that it permits slippage and eliminates the possibility of breakage of the parts. Also with a clutch mechanism of this type, the speed of operation of the driven shaft may be varied by means of the band brake thereon. The controlling parts are closely and conveniently arranged; a platform 38 being arranged on the rear of the frame to receive an operator.

While I have shown and described but one form of device herein, it will be understood that the same is susceptible of modification and, therefore changes in the construction and arrangement of the several parts may be employed without departing from the spirit of my invention as disclosed in the appended claims.

The cleats 19, as will be seen from an inspection of Fig. 1 are arranged in comparatively close relation with the sides of the frame bars, and thus serve to hold the scraper against endwise movement.

There is a further advantage in connection with the flexible suspension links for the scraper and the pivoted connections for the draft bars both with the scraper and the frame, which is found in the fact that vibratory movements of the frame, imparted by the rise and fall of the draft vehicle over uneven ground, are not transmitted to the

scraper, and therefore the angular position of the latter at work remains substantially constant and there is not present any variable depth of cutting such as would be caused if the suction or pitch of the blade 70 were undergoing continual disturbance.

A further feature of importance, also, where positive means are provided for depressing the scraper, is the yielding or frictional brake device for holding the scraper 75 to its work. A positive lock for this purpose would be disastrous to the machine, whereas the present device is sufficiently secure for normal conditions and will yield to permit the scraper to ride over obstructions.

Having thus described my invention, what I claim and desire to secure by Letters Patent is—

1. In a land leveler, a frame, a scraper, a pair of vertical bars connected at their lower ends to the scraper, rack bars pivotally connected at their lower ends to the vertical bars, standards extending upwardly from the frame, a shaft journaled in said standards, pinions on the shaft meshed with the teeth of the rack bars, means on the frame bearing against intermediate parts of the rear sides of the vertical bars to hold the latter against rearward movement, yokes 90 on the standards receiving the rack bars, spaced means borne by the yokes and engaged with the upper end parts of the rack bars to hold same in mesh with the pinions, and means to operate the shaft. 100

2. In a land leveler, a frame, a scraper, a pair of vertical bars connected at their lower ends to the scraper, rack bars pivotally connected at their lower ends to the vertical bars, pinions mounted on the frame 105 in mesh with the rack bars, means engaging the rear sides of the vertical bars to hold same against rearward movement, means engaging the rack to hold the pinions in engagement therewith, and means to operate 110 the pinions.

3. In a land leveler, a frame, a scraper, vertically adjustable rack bars on the frame, rigid members connected to the scraper, means to hold the members against rearward movement, said members being engageable with opposite sides of the frame so as to hold the scraper against movement transverse of the frame, and means for pivotally connecting the lower ends of the rack bars to the members to allow the rack bars to flex independently of the members. 120

4. In a land leveler, a frame, a scraper, rigid vertical members adjacent the scraper ends engageable with opposite sides of the frame, means to slidably support said members from the frame to hold the members against rearward movement, means to raise and lower the scraper, and a series of draft links inclining downwardly toward the 130

scraper, the links being arranged to form a pair of outer divergent links connected to the scraper adjacent the outer ends and bottom of the latter, and a central link between the pair of links and between the members and connected to the scraper adjacent the center and bottom of the latter.

5. In a land leveler, a wheeled frame, a scraper beneath the frame, means to pivotally connect the lower portion of the scraper to the front of the frame, vertical members connected to the scraper to support the upper portion of the same against rearward movement and projecting upwardly therefrom, means on the frame engaging the upwardly projecting parts of said vertical members to hold same against rearward movement, raising and lowering elements pivoted at their lower parts to said vertical members, and means to effect raising and lowering of said elements.

6. In a land leveler, a frame including side members inclined downwardly and converging at their forward end portions, a scraper arranged below the frame, links pivoted to the forward end of the frame and inclining downwardly at their rear ends and pivotally connected with the scraper adjacent the bottom of the latter, vertical members connected to the scraper to support the upper portion of the same against rearward movement and projecting vertically past the frame, means on the frame to

prevent rearward movement of the upper parts of the vertical members and which 35 permits them to move vertically, and means to raise and lower the scraper.

7. A land leveler as specified in claim 6, in which the scraper raising and lowering means embodies racks having pivotal connection at their lower ends to the rigid vertical members, pinions meshed with the racks, and means to hold the pinions and racks in mesh.

8. In a land leveler, a wheeled frame, a scraper beneath the frame, means to pivotally connect the scraper to the front of the frame, vertical members connected to the scraper and projecting upwardly therefrom, means to raise and lower the scraper, 50 and means engaging the vertical members to prevent rearward movement thereof in all positions of the scraper, said means pivotally connecting the scraper to the frame and said members being both connected to 55 the scraper so that during forward movement of the frame the impelling supports on the scraper will occur at the lower and upper portions thereof.

In testimony whereof I have hereunto set 60 my hand in the presence of two subscribing witnesses.
